FURNACE WITH REFLEX ARCH

Paul Wright, Birmingham, Ala.

Application October 16, 1939, Serial No. 299,665

11 Claims. (Cl. 110—72)

This invention relates to furnaces, and particularly such boiler and industrial furnaces as utilize the various forms of wood fuels, refuse and other adaptable fuels.

The general object of my invention is to provide, as a substitute for the customary dutch oven furnace, an improved furnace effecting a reflex movement of the furnace gases over fuel therein moving progressively; a furnace attaining higher furnace temperatures with attendant hastening of fuel burning; a furnace having an improved regulation and proportioning of combustion air through the fuel and over the fuel.

A further object is to provide such furnaces with protection of the grates and related parts against heat; to facilitate the removal of ash and cinder; to provide improvements in furnace enclosures to retain and utilize heat and reduce maintenance costs.

Another object is to provide a furnace that utilizes a reflex arch that is exposed to furnace heat on both sides, whereby intense heat can be reflected below and above said arch within the furnace.

One feature of the invention is the provision for gravitational placement of fuel to transversely cover the grate uniformly and repose in greater thickness upon a lower adjoining hearth in combination.

Another feature of the invention is the provision for a steam generator, of a wood refuse burning furnace capable of sustaining high performance ratings, without employing supplementary fuels like oil or gas.

The various features of novelty which characterize my invention are pointed out with particularity in the claims annexed to and forming a part of this specification. For a better understanding of the invention, its operating advantages and specific objects attained by its use, reference should be had to the accompanying drawings and descriptions in which I have illustrated and described preferred embodiments of the invention.

Of the drawings:

Fig. 1 is a longitudinal section illustrating one embodiment of my invention.

Fig. 2 is a transverse vertical section taken at line 2—2 as shown on Fig. 1.

Fig. 3 shows by enlarged view, the gas passages indicated at section 3—3 in Fig. 1.

Fig. 4 is a longitudinal section illustrating a modification embodying the invention.

Fig. 5 is a transverse vertical section on line 5—5 of Fig. 4.

Fig. 6 is an enlarged view of the uppermost grate rest.

Fig. 7 illustrates the application of the reflex arch and imperforate hearth, to the type of dutch oven furnace shown.

Fig. 8 furnishes an enlarged sectional view of the fluid cooled tubes as taken at 8—8 in Fig. 7.

In the furnace embodying my invention illustrated by Figs. 1 and 2, a front wall 1 closes 10 the portion forward of the grates, and an upward continuation 2 and 3 provides a front wall portion, along which entering fuel is fed into the furnace. Fuel is delivered thru an opening 4, preferably across the entire furnace width; or there may be a series of openings 4 located transversely as shown. One form of roof enclosure comprises a shape bounded by portions 5, 6 and 7 as illustrated in Figs. 1 and 4. A wall 8 on each side extends upward from the foundations 9, on which the structure rests.

As the illustration of Figs. 1 and 2 shows the relation of the furnace to a steam generator, I designate the lowermost water chamber 10, from which water is conveyed thru pipes 11, 12 and 13 to a tube header 14 at the upper front. A plurality of spaced tubes 15 extend from header 14, to a steam and water chamber 16. The assembly of pipes and tubes in combination with the steam generator forms a path of flow of water from chamber 10 to chamber 16. The spaced tubes 15 may be incased along portions 5 and 6, with blocks and spacers similar to the constructions covered by my patent application Serial 294,568 of 1935 series; or otherwise the space about tubes 15 is closed with refractory between same.

A front row of tubes 17 support an upper front baffle 18 thru which spaced openings 19 pass furnace gases between tubes 20 and 21 beyond, whereby upper stratification of gases is relieved. Baffle 18 constitutes a downward continuation of the furnace roof 6, as defining the uppermost rear closure of the furnace of Fig. 1. The primary heating surface of the steam generator is comprised of tubes 17, 20 and 21.

The fuel support comprises a lowermost transverse grate support 22 upon which in close contact, is placed rest bar 23 as shown by Fig. 1. This construction supports the lower ends of grates 26, and resists the downward thrust caused by the weight of grates and fuel thereon. The masonry structure 31 beneath is an added safeguard to resist deflection of the beam 22. Said masonry structure also functions as a furnace hearth in combination with said grates adjoin-

ing same. The hearth slopes as shown or it can be level.

An intermediate transverse grate support 22a with grate rest bar 24, is used to hold up the grate ends that abut. An uppermost transverse grate rest 25 is also illustrated by an enlarged view Fig. 6, which shows how air passage is arranged and provision made for the upper grate ends to slide due to expansion or contraction.

The upper structural front 28 holds wall 2 and 10 3, supports header 14 slidably and fastens to upper rest bar 25 as shown. Access to grates for advantageously cleaning, while the furnace is in operation, is afforded by openings 29 whereby a steam lance can be used to blow thru the grate 15 openings or, in cases of excessive accumulation of ash or fused matter, a slice bar can readily be used. Upper grates 27 or upper parts of grates 26 generally have a minimum of clinker.

Natural draft air admission to the furnace setting beneath grates, may be thru draft doorways 30, that also serve for ash removal.

As an extension for supporting the fuel beyond the lowermost ends of grates 26, I provide a hearth 31 made preferably of refractory having arched 20 passages 32 beneath as shown by Figs. 1 and 2. The number and location of ash doorways 30 is arranged to suit passages 32 for easy ash removal. Forward of passages 32, I provide one or more draft gates 33 that are raised or lowered by chain 34 which passes thru front wall 1. Keeping the chains taut will hold the gates 33 from leaning, however gate guides may be used. To effect a complete closure downward from lower grate support 22, I employ a partition 36 that extends 30 transversely and fastens at the lower side to guides 35. Thus with gates 33 raised, air thru the front side may pass thru passages 32 or thru grates above or thru both, depending on conditions of fuel bed effecting resistance to air flow. 40 This partition 36 may be sloped to shed ashes from grates 26 to the floor forward of gates 33.

For introducing forced draft beneath grates only, with gates 33 down or closed, I provide a passage 31, preferably thru the side wall 8 and forward of partition 36; however, if gates 33 be raised, this forced draft may also pass thru passages 32. I have found that the height that gates 33 are open, will somewhat tend to proportion the air flow between grates and arched passages 32 but not with adequate control. I therefore have embodied in my invention, another source of forced draft thru opening 38 which is rearward of the partition 36. This arrangement of air inlets thru passages 39, 37 and 38 provides several combinations of air supply beneath the fuel thru grates and over the fuel from passages 32 below, in an improved distribution.

In prior furnace constructions of the general character described and with either flat or inclined fuel supports, the furnace gases flow away from the fuel bed in the most direct route to the furnace chamber's exit. Thus in the case of moderately wet hogged wood fuel, the moisture and volatiles gasify and rise toward the furnace roof and pass outward before air thru the fuel bed can reach or mix with same.

"Hogged fuel" is usually made from wood that is waste such as scraps, trimmings, edgings with bark; and these are chipped, macerated and reduced in size thru a machine called a "hog," whence the term. Wood refuse fuel often comprises varied mixtures of "hogged fuel" with saw dust, shavings, bark waste and the like, which pass by conveyor to a fuel storage.

Heretofore endeavor has been made to "retard the gas flow" under such circumstances, with the intended purpose to accomplish most of the combustion in the primary furnace. This retarding has not been practically accomplished especially at forced rates of firing. Furthermore, the late addition of needed air for combustion at a zone beyond the primary chamber's exit, does not promote as good combustion as is accomplished by earlier distributing air in the gas distillation zone and under high temperature conditions. And still further, the admission of air thru the roof of the furnace and at the fuel entrances has a chilling effect, reducing the roof's useful radiation effect, and air thru the roof is not as desirable as supplying air lower down close to the fuel bed. Various arrangements have been tried or introducing air thru the bridge wall on its forward side and such openings invariably clog or close by slagging, affording only temporary inlets and thus it is difficult to avoid undesirable air variations.

Air passing thru the bridge wall at high velocity towards the fuel, tends to waft light fuel to settle beyond unburned, unless burned in transit. Also admitting air thru the rear of bridge wall results in lanning of gases and insufficient mixing, whereby combustion is not completed.

Noticeably dutch oven furnaces operating at high ratings with refuse materials as fuel, often employ supplementary combustion chambers in 30 which other fuels such as oil, gas or powdered coal are relied on to produce high temperature radiant exposures that will aid in consuming the carry-over of unburned fuel, as previously described.

To facilitate improvements in fuel burning, as compared with the dutch oven operations just described, I have invented a furnace construction embodying a reflex arch as illustrated in part by Fig. 1, Fig. 4 and Fig. 7. The furnace may also comprise in part, a transverse ash pit 39 spaced beyond the refractory hearth structure 31 and closed on the rear by a transverse bridge wall 40. Refractory lined doorways 41 in either or both side walls 8 afford access for raking out or for inspection. Adjoining the transverse wall 40 above and inclining over the pit 39 and hearth 31, there is extended a reflex fluid cooled arch 42 which spans the furnace between side walls 8. This reflex arch 42 inclines somewhat parallel to the grate surface but not necessarily.

In the case of wide furnaces it is optional to provide a furnace partition wall 43 as shown in Figs. 1 and 7. This wall 43 is not illustrated in Fig. 4. The partition wall 43 is arranged across 55 the pit 39 and hearth 31 so as to extend upward to the arch 42 and is usually located midway between the side walls 8. Wall 43 is advantageous to absorb heat, which can be radiated when wet fuel enters the furnace or when the grates 26 are cleaned, with fire retained on hearth 31. Side access doorways 44 are placed in side walls 8 also just above the top of hearth 31, there are provided appropriate doorways 45 for slicing clinker off hearth 31 into pit 39 below.

For further facilitating ash or clinker removal in combination with raising gates 33, I provide a transverse trench 46 which is covered by removable plates 47 whereby with plates 47 in place, the rakeout is over same thru doors 30 or 70 with plates 47 removed, ash is deposited in trench 46, to be moved away, and thereafter plates 47 are replaced to cover 46.

Referring particularly to Fig. 4, I have shown 75 an approximate upper contour of the fuel when

burning wet hogged southern pine; also from my observations made in practice, I have shown the travel of combustion flames and gases. In like manner in Fig. 1, by means of arrows I show the direction of flow of air and gases thru the furnace and beyond. In Fig. 4, I illustrate the preferred placement of fuel on the grates 26 and hearth 31, whereby the thickness of the fuel bed gradually increases to a maximum thickness over the hearth 31 and beneath arch 42. The fuel uniformly can cover the grate transversely of the furnace, which facilitates a controllable passage of air thru the fuel without blowing holes thru the fire bed.

It is practical to operate the illustrated embodiments of my invention by providing natural draft alone thru doors 30; natural draft thru doors 30 along with forced draft thru passages 32 from inlet 38 with gates 33 closed or down; forced draft from inlet 37 and doors 30 closed, thru gates alone with gates 33 closed or thru grates and passages 32 with gates 33 lifted, as desired. Another useful method of air supply is to supply forced draft thru openings 37 and 38 with gates 33 closed, and being supplied from a single source without the furnace or from separate individual sources as may be desired. Damper controls on ducts to 37 and 38 from the same source of air supply will separately vary the flow thru gates and over fuel under the reflex arch. Again, separate sources of air supply thru openings 37 and 38 permit variations in air quantity and pressures beneath the fuel and over the fuel.

Heretofore grates in many wood burning furnaces have given trouble due to overheating and clinkering; various forms of pusher bars have been tried to advance fuel and move clinker; also disposal of ash and clinker has caused costly repairs and shut-downs. Further record of such operating difficulties with pusher grates, is the trial usage of these in combination with water-cooled tubes; however such means does not eliminate the causes of depositing slag or cinder on said grates. My invention improves upon these conditions as will be understood from my specification and illustrations of this invention, as pertains to these features.

In the present construction, instead of using dump grates or the equivalent, to dispose of clinker that may collect at the lower section of the grates, I employ an inclined hearth in combination with a reflex arch above, whereby the heat is so intense as to melt and collect and run off the clinker as illustrated in Fig. 4 at top of hearth 31. Spilled fuel in the rear of pit 39 burns intensely with air thru passage 32 and bridge wall 40 reflects heat against a thick mass of charred fuel in the region or elevation of door 44. Thus ash, sandy matter and the like, settle to the bottom of the fuel on hearth 31, indicated at 70. If clinker gathers on lower ends of grates 26, it will generally melt and run downward to the hearth; yet while it is soft, it can be sliced from doors 29 if it adheres to the grates. Use of a steam lance at necessary intervals will remove from the grates such ash, sand and substances that make clinker, before they become sticky or viscous. When the furnace is operating at lower than average temperatures, the doors 45 may be used to slice hardened clinker off the hearth and a cleavage between the hearth and clinker is assisted by utilizing the cooling section, employing tube 55 as shown.

Heretofore in dutch ovens, an inclined step

grate arranged with a dump grate at the lower part has been used, and endeavor has been made to control the thickness of fuel bed by a width of throat at the fuel entrance whereby the fuel 5 would burn out by the time it progressed to the dump grate, thus intending to provide a thin fire at the bottom enabling ash and clinker to be dumped; but experiences show such dump grates are not satisfactory because the fuel at times 10 avalanches over same and against an adjacent bridge wall and results in clinkering and burning of the lower grates.

This burning is due to intense heat above and 15 air passages being partly stopped by slagging on the dump. Again, step grates have been used without a dump grate where the fuel regularly avalanches onto a shelf, to pile up against the adjacent bridge wall and at an elevation below the ends of said grates. Here also a deficiency 20 of air needed over the fire occurs, as air does not suitably pass thru this piled fuel where ash and cinder accumulate on the said shelf.

An improvement wanted in fuel burning, is 25 accomplished with my new combination of a fuel support having a lower hearth adjoining an ash pit open to the furnace and a reflex arch directing the gases of combustion, all in the manner described and as shown by the drawings.

With further reference to the specification of 30 the reflex fluid cooled arch 42, shown by Fig. 1, it comprises various blocks supported by single tubes 55 and double tubes 56 extending across the furnace and resting on side walls 8. The tube acts as a beam and a preferred material 35 would be seamless steel tubing of a size and strength calculated to resist the weight of fuel and the blocks forming the arch.

As a means of practically constructing my 40 reflex arch in extended widths, another preferred form of support comprises two tubes 56 as illustrated in Figs. 1 and 7. The double tubes 56 are incased with blocks and spacers as shown and furnish a stronger and stiffer beam than the same size single tubes 55 shown.

45 In the wall 40 of Fig. 7 where tubes 55 appear, a means of facilitating the erecting of tubes is shown by Fig. 8 which is a partial section at 8-8 where tubes 55 pass thru wall 8. A clearance space 64 above each tube 55 in wall 8 is provided and this may be packed with removable mineral wool for example. Thereby the tubes are free to slightly move with the inner arch or wall which expands more than the outer part of wall 8 which is exposed to atmosphere.

The use of tubes 55 as utilized in the wall 50 bounding refractory hearth 31, serves to strengthen the construction by bridging the upper parts of arches over passages 32.

From the foregoing descriptive specification of 60 the reflex arch construction, it will be apparent that the inclination of the arch 42 can be suited to the upper contour of the fuel bed in a manner to direct combustion air from pit 39 so as to be in intimate contact with the fuel as shown by Fig. 4. The extent of coverage of the reflex arch over the fuel bed is not limited by structural features of support.

In Fig. 7, I show how this dutch oven furnace was improved by providing the hearth 31, ash 65 and slag pit 39, in combination with wall 40 and arch 42b. Also the partition wall 43a is retained, the forward lower side of which was aligned with a bridge wall that was removed.

Heated air and gases from the fuel bed and 70 pit below, pass far enough forward by means of

the reflex arch, to aid in heating and gasifying the entering fuel on the upper fuel support.

Heretofore furnaces have been adapted to retain a thin bed of fuel in an inclined position with a forwardly sloping wall spaced therefrom to form a combustion chamber between, said wall extending upwardly to the level of the upper grate; but such constructions fail to provide my improvements utilizing the thick lower fuel bed, spaced close to my reflex arch for intensifying burning, with air admitted over the fuel from low down passages.

The reflex arch favors burning a thick fuel bed at the lower part of the fuel support whereby refuse in larger sized pieces can be burned under its intense reflected heat, yet the lower grates are protected by the thick fuel as well. Also the thick fuel bed enables carrying a banked fire not practical with a thin fuel bed.

The reflex arch effectually lengthens the gas travel from the lower part of fuel to exit of the furnace, by reason of the longer reflex path of passage, as compared with that in the customary dutch oven employing an approximately vertical bridge wall. The invention provides an improvement in the rate and completeness of burning.

The combination of hearth 31 and arch 42 intensifies burning to the extent that grates 26 can be provided with small perforations or without perforations if desired.

The reflex arch being safely and practically held in position by fluid cooled tubular supports, it can withstand fire on both exposed sides whereby the upper side can usefully serve to radiate and reflect to the furnace chamber above and gases traversing it. Practice shows fuel does not remain unburned over this arch.

Concerning the dutch oven roof construction as illustrated by Fig. 7, it has been common to suspend refractory tiles to match a desired furnace roof contour. While such roof tiles are replaceable, the heat radiation loss and the maintenance cost is greater, than that of my fluid cooled roof 5, 6 and 7 of Figs. 1 and 4.

By illustrating preferred shapes of furnace roof enclosures 5 and 6 as in Figs. 1 and 4, I desire to show that an enclosure of this type can be suited to various furnace and reflex arch constructions as related to boilers, in a manner to withstand intense furnace temperatures economically and accommodate reflex movement of the combustion gases as described.

It is practical and desirable to feed fuel across the furnace width thru entrances 4 as shown by Fig. 1 and Fig. 4 and between the spaced tubes 15.

Before the dutch oven of Fig. 7 was remodeled by adding the hearth 31, pit 39, wall 40 and arch 42b of this invention, it was customary to provide a thin fuel bed at the bottom of grates 26a, also air entered thru dump grates adjoining the lower ends of grates 26a. A fuel bed thick at its lower part similar to that of Fig. 4, would therefore hinder air passage thru the lower grates 26a if employed in the furnace of Fig. 7 not equipped with the above named hearth, pit, wall and arch. Hence the disadvantage of slagging on dump grates is avoided by improving the furnace like Fig. 7 shows. It usually requires more than an hour daily to clean one set of dump grates of slag, and the time and expense saved by my invention makes it useful to facilitate continuous furnace performance.

In the case of burning light comparatively dry

wood shavings, it is possible with excessive forced draft and a thick fuel bed, to waft unburned shavings beyond the reflex arch, therefore I provide a drop combustion chamber 66 as shown in Figs. 1 and 4. The ratio of hearth length to grate length can be advantageously increased when burning shavings; and in such case the hearth can be approximately level, since dry shavings make less ash than "hogged fuel" which may contain sand. The fuel on the floor at 66 will burn readily upon admitting air thru doorway 67, provided the chamber is hot enough to promote combustion. If the chamber is only moderately hot, an improved means for rapidly burning the fuel, only to clear the floor, is had by employing a steam jet thru openings 68 as shown in Fig. 1, and air is admitted thru openings 68 thereby.

In the present construction shown by Figs. 1 and 4, I employ a baffle 69 that is supported by tubes 20 and 21, as a means to direct the furnace gases rearward over the reflex arch and thence over the steam generator's primary heating surface. A special feature that eliminates a "gas pocket" in the uppermost furnace chamber adjacent said steam generator at the top of baffle 69, provides for gas passages 19 as shown by Figs. 1 and 3. Similar passages in Fig. 4, are designated at 19a. These openings 19 and 19a, serve to shunt upward portions of the combustion gases, which causes floating unburned fuel to rise in a flurry that increases its time in transit and improves burning of same. In Fig. 1, the perforate baffle 18 corresponds to a downward extension of the roof 6, to adjoin baffle 69, with the openings 19 occurring just above the baffle 69.

I have previously stated that my invention utilizes "other adaptable fuels." For example, as an overfeed method of firing coal, the novel imperforate hearth functions to reduce slagging of the grates. Furthermore, coals that have "low temperature fusion of ash" properties, will burn in improved manner, since the ash can melt on the hearth and pass to the slag pit.

While in accordance with the provisions of the statutes I have illustrated and described herein the best forms of the invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. In combination with a furnace: side walls, a front wall and a furnace roof, extending between the side walls, and a fuel entrance into said furnace; within the furnace, a transverse imperforate hearth spaced inwardly from said front wall, a transverse fuel support comprised of inclined grates that upwardly adjoin said front wall and downwardly adjoin said imperforate hearth; a lower ash pit inwardly of and adjacent said hearth, said hearth sloping to and terminated by said transverse lower ash pit; a door in the side wall at said pit; a heat reflecting bridge wall adjacent to the hearth but spaced apart by said pit therebetween; a heat reflecting arch joined to said bridge wall and extending over, and spaced apart from, said pit and hearth; said arch being imperforate and extending upwardly toward said roof but spaced apart therefrom, to provide a furnace passage therebetween; the combination being capable of effect-

ing the reduction of slag on said grates by accumulating the slag on said hearth, from whence it can pass to said pit.

2. The construction of claim 1, in combination with a door in the side wall and said door situated to enable the operator to slice slag off said hearth into said pit.

3. In a furnace, fuel burning apparatus comprising, a furnace front wall, furnace side walls and inclined perforate grates that extend from said front wall transversely between the side walls; a furnace imperforate roof extending between the side walls and to said front wall, and a fuel entrance into said furnace; a level imperforate hearth adjoining the lower transverse edge of said grates; an ash pit arranged at the rearward transverse edge of said hearth and a door in the side wall to said pit; a bridge wall across the furnace and so arranged that said bridge wall and hearth form opposite sides of said pit; a reflex imperforate arch that adjoins said bridge wall and thence extends relatively close to said hearth and grates; said arch extending upwardly toward said roof but spaced apart therefrom, to provide a furnace passage therebetween; an air supply chamber that is partially bounded by the furnace front wall, and said side walls, and by said grates above the chamber; said front wall having air entrance doors therein; means forming passages under said hearth to connect said air chamber to said pit; doors arranged in the front wall of said air chamber, whereby an operator can clean said grates by ejecting residue on to said hearth whence the residue can be passed to said pit.

4. In combination with a furnace for burning solid fuel: side walls, a front wall and a furnace roof extending between the side walls, and a fuel entrance into said furnace; within the furnace,—an inclined imperforate hearth, an ash pit extending transversely of the hearth, a transverse fuel support comprised of an inclined grate surface that upwardly extends to said front wall and downwardly adjoins said imperforate hearth the pitch of said hearth being less than the angle of repose of the fuel to be burned, and less than that of the inclined grate; said hearth sloping to and terminated by said ash pit; a heat reflecting bridge wall adjacent to the hearth but spaced apart by said pit therebetween; a heat reflecting arch joined to said bridge wall and said arch extended over, and spaced apart from, said pit and hearth; said arch being imperforate and arranged to provide a fuel burning passage between said fuel support and said arch, whereby fuel in large pieces will repose on the fuel support without substantially spilling into said pit, facilitating the burning of said fuel which is subjected to intense reflected heat.

5. In combination with a furnace for burning solid fuel: side walls,—a front wall and a furnace roof, extending between the side walls, and a fuel entrance into said furnace; within the furnace an inclined imperforate hearth, an ash pit extending transversely of the hearth, a transverse fuel support comprised of inclined grates that upwardly adjoin said front wall and downwardly adjoin said imperforate hearth the pitch of said hearth being less than the angle of repose of the fuel to be burned, and less than that of the inclined grates; cleanout doors arranged in the side walls, above said grates; said hearth extending to and terminated by said ash pit; a door in each side wall at said pit; a heat reflecting bridge wall adjacent to the hearth but spaced apart by said

pit therebetween; a heat reflecting arch joined to said bridge wall and extending over, and spaced apart from, said pit and hearth; said arch being imperforate and extending upwardly toward said roof but spaced apart therefrom, to provide a furnace passage therebetween; a partition wall arranged under said arch and across said pit and hearth; the combination enabling burning fuel to be held on said hearth, with said grates bare of fuel,—thereby permitting said grates to be cleaned while fire is retained in said furnace and heat is maintained in said partition wall to aid combustion.

6. In a furnace, for burning solid fuel, a slaggering hearth,—inclined grates for supporting fuel and said grates adjoining and extending upwardly from said hearth; an ash and slag pit arranged along the lowermost transverse edge of said hearth; an air chamber arranged beneath and partitioned apart from said grates, means forming passages arranged to connect said air chamber to said pit, which passages extend under said hearth; a bridge wall across the furnace and arranged so that said bridge wall and hearth form opposite sides of said pit; a reflex imperforate arch that adjoins said bridge wall and thence extends relatively close over said hearth and grates, said arch extending upwardly with its upper transverse edge arranged over the upper transverse edge of said hearth; whereby air for combustion will pass by way of said pit and beneath said arch in the furnace, facilitating progressive burning of the fuel.

7. In a furnace, fuel burning apparatus comprising,—a furnace front wall, furnace side walls and inclined perforate grates that extend from said front wall transversely between the side walls; a furnace imperforate roof extending between the side walls and to said front wall, and a fuel entrance into said furnace; an imperforate hearth adjoining the lower transverse edge of said grates; an ash pit arranged at the rearward transverse edge of said hearth and a door in the side wall to said pit; a bridge wall across the furnace and so arranged that said bridge wall and hearth form opposite sides of said pit; a reflex imperforate arch that adjoins said bridge wall and thence extends relatively close over said hearth and grates; said arch extending upwardly toward said roof but spaced apart therefrom, to provide a furnace passage therebetween; an air supply chamber having air entrance doors therein; said chamber bounded by said furnace walls, and by said grates above the chamber; means forming passages with gateways and arranged to connect said air chamber to said pit by extending said passages under said hearth; whereby said apparatus,—provides for air of combustion to pass thru said grates, also provides separately for air of combustion to pass by way of said pit wherein it is heated, thence beneath said reflex arch in the furnace.

8. In a furnace utilizing a combination of two sources of air for combustion, a front furnace wall and side walls; inclined perforate grates that extend from said front wall, transversely between the side walls; a lower hearth adjoining the lower transverse edge of said grates; an ash pit arranged at the rearward transverse edge of said hearth; a bridge wall across the furnace and so arranged that said bridge wall and said hearth form opposite sides of said pit; and as one source of air supply, a grate air chamber arranged under said grates and partially bounded by, said front wall and said side walls, and a gated partition

that adjoins the lower transverse edge of said grates at said hearth; access doors in said front wall whereby air enters forward of said partition into said grate chamber; and as another source of air supply, a pit air chamber arranged below said hearth and connected with combination air and ash passages extended under said hearth to said pit; a door in said side wall whereby air enters said pit chamber, rearward of said partition; whereby the combinations of air thus supplied, facilitate the hastening of fuel burning with higher temperatures in the furnace; and said passages advantageously permit removal of ash, thru said gated partition and said front wall access doors.

9. In a furnace utilizing "hogged wood" as fuel: a front furnace wall, furnace side walls and inclined perforate grates that extend from said front wall transversely between the side walls; a furnace imperforate roof extending between the side walls and to said front wall, and a fuel entrance into said furnace; a lower imperforate hearth adjoining the lower transverse edge of said grates; an ash pit arranged at the rearward transverse edge of said hearth; a bridge wall across the furnace and so arranged that said bridge wall and hearth form opposite sides of said pit; a reflex imperforate arch that adjoins said bridge wall and thence extends relatively close over said hearth and grates; said arch extending upwardly toward said roof but spaced apart therefrom, to provide a furnace passage apart therefrom, to provide a furnace passage therebetween; said hearth having an inclination less than the angle or repose of the fuel and less than that of the grates, so that fuel will repose on the hearth in greater thickness than on said grates and without substantially spilling into said pit; an air chamber that is partially bounded by the furnace front wall and side walls, also by said grates above the chamber; also said chamber bounded further by a gated partition that zones air between said grates and passages that are arranged to connect said air chamber to said pit, and said passages arranged under said hearth; a door in the side wall for air entering said passages as partitioned from said air chamber: whereby air passes to the furnace thus; with the gates of said partition open, air passes from said chamber thru said grates also thru said passages to said pit; furthermore with the gates of said partition closed, air passes from said chamber thru said grates, and separately air entering thru said door in the side wall as partitioned off, passes via said passages to said ash pit, thereby enabling improved regulation and proportioning of combustion air thru the fuel and over the fuel.

10. In a furnace burning "hogged wood" as fuel, fuel burning apparatus comprising, a fur-

nace front wall furnace side walls and inclined step grates that extend from said front wall transversely between the side walls; a furnace imperforate roof extending between the side walls and to said front wall with a fuel entrance into said furnace; a lower imperforate hearth adjoining the lower transverse edge of said grates; an ash pit arranged at the rearward transverse edge of said hearth and a door in the side wall to said pit; a bridge wall across the furnace and so arranged that said bridge wall and hearth form opposite sides of said pit; a reflex imperforate arch that adjoins said bridge wall and thence extends relatively close over said hearth and grates; said arch extending upwardly toward said roof but spaced apart therefrom, to provide a furnace passage therebetween; an air supply chamber that is partially bounded by the furnace front wall and side walls, also by said grates above the chamber; access doors in said furnace walls whereby air enters said chamber; passages with gateways, arranged to connect said air chamber to said pit by extending said passages under said hearth; said hearth having an inclination less than the angle or repose of the fuel and less than that of the grates, so that "hogged fuel" will pass over the grates to pile on the hearth without substantially spilling into said pit also the fuel will repose thicker over said hearth than over the upper area of said grates, thereby providing protection of said grates against furnace heat and air of combustion passed beneath said arch in the furnace.

11. A furnace with reflex arch, having in combination: side walls, a front wall and a furnace roof extending between the side walls and a fuel entrance into said furnace: within the furnace, a transverse imperforate hearth spaced inwardly from said front wall, a transverse fuel support comprised of inclined grates that upwardly adjoin said front wall and downwardly adjoin said hearth; a lower ash pit inwardly of and adjacent said hearth, said hearth sloping to and terminated by said ash pit; a heat reflecting bridge wall adjacent to the hearth but spaced apart by said pit therebetween; a reflex arch joined to said bridge wall and extending over, and spaced apart from, said pit and hearth; said arch being imperforate and extending upwardly toward said roof but spaced apart therefrom to provide a reflex passage of the combustion gases therebetween; and said furnace extended rearward over said reflex arch so as to provide a drop combustion chamber rearward of said bridge wall, whereby unburned fuel carried over said arch will burn within the drop combustion chamber.

PAUL WRIGHT.
